UNITED STATES PATENT OFFICE

100,345

DESIGN FOR A SPACE HEATER

Henry C. Caldwell, Buffalo, N. Y., assignor to
Hendwell Corporation, Buffalo, N. Y., a corpora-
tion of New York

Application November 6, 1935, Serial No. 59,402

Term of patent 14 years

To all whom it may concern:

Be it known that I, Henry C. Caldwell, a citizen of the United States, residing in the city of Buffalo, county of Erie, and State of New York, have invented a new, original, and ornamental Design for Space Heaters, of which the following is a specification, reference being had to the accompanying drawing, forming part thereof. In the drawing:

Fig. 1 is a front elevation of the heater.

Fig. 2 is a plan view thereof.

Fig. 3 is a fragmentary, sectional view of the body taken on line 3—3 of Fig. 1.

Fig. 4 is a sectional view of the cover taken on line 4—4 of Fig. 2.

Fig. 5 is an enlarged, fragmentary, sectional view of the body and is taken on line 5—5 of Fig. 5.

All sides of the heater are substantially like that shown in Fig. 1.

I claim:

The ornamental design for a space heater, as shown and described.

HENRY C. CALDWELL.
